ATTORNEY

UNITED STATES PATENT OFFICE.

GEORGE K. CHENEY, OF NEW YORK, N. Y.

MECHANICAL MOVEMENT.

SPECIFICATION forming part of Letters Patent No. 623,133, dated April 18, 1899.

Application filed August 16, 1898. Serial No. 688,676. (No model.)

To all whom it may concern:

Be it known that I, GEORGE K. CHENEY, a citizen of the United States of America, and a resident of New York city, New York county, 5 New York State, have invented certain new and useful Improvements in Mechanical Movements, of which the following is a specification.

My invention relates to mechanical movements or mechanism for producing motion or controlling of same, and is more specifically designed to produce a simple, noiselessly-running and easily controlled and adjusted train of mechanism for rotating a horizontal table 10 such as that on which rest the disk-shaped sound-records produced on and employed with what is known as the "gramophone." The elements of such train of mechanism consist generally of power-driven gearing usually 15 set in motion by a spring and a governor for controlling the rate of rotation and the rotating vertical shaft on which the table is mounted, which is most conveniently, if not necessarily, placed between the driving-gear and 20 the governor. In such a train of gearing as ordinarily constructed, in which the bearings of the various shafts and gear-wheels are all rigidly fixed in their relation one to another, it is practically impossible to turn out a large 25 number of sets of apparatus which when put together will run smoothly and with that absence of noise which is absolutely necessary in a talking-machine. I have overcome this difficulty and at the same time produced a 30 cheap and simple apparatus by mounting the driven shaft, to which the rotating table is attached, in a frame which is adjustable on and removable from the bed-plate of the mechanism, so that the gear-wheel and pinion 35 carried thereby may in each particular case be adjusted to exactly the right position with reference to the driving-gear and the governor-pinion by the operator who is assembling the machines.

40 The preferred form of apparatus in which my invention is embodied is illustrated in the accompanying sheet of drawings, in which— Figure 1 is a plan view of the apparatus. Fig. 2 is a side elevation with a part of the 45 bed-plate broken away. Fig. 3 is a detail,

partly in elevation and partly in section, showing the governor.

Throughout the figures of the drawings like reference-figures refer to like parts.

1 represents the bed-plate, on which rests 55 the separate adjustable frame 2. The adjustment of said frame 2 with reference to the bed-plate is best secured by means of the slots 3 and 4 in the base of the adjustable frame and the set-screws 5 and 6 or their equivalent 60 passing through said slots and screwing into the bed-plate 1. In order to render possible an endwise adjustment of said frame, as well as sidewise adjustment, I preferably form the inner portion of said slots 3 and 4 in the shape 65 of two cross-slots 3^a and 4^a. In this adjustable frame 2 is housed the vertical shaft 7, on which is keyed or otherwise secured the rotating horizontal table 8.

9 is an internally-threaded disk which 70 screws down on the end of the shaft 7 to hold the ordinary gramophone-record or other plate placed on the table in position. On the vertical shaft 7 are fastened the toothed gear-wheel 10, held in place by the set-screw 11, 75 and the pinion 12, held in place by the set-screw 13 or equivalent means. The shaft is driven by means of the pinion 12, which meshes with the driving-gear 14. This driving-gear may be operated by any suitable 80 train of gearing driven by power. I have illustrated the train of gear-wheels 15 16 16^a, the latter being driven by the ordinary clock-spring 16^b. The rate of rotation is controlled 85 by means of the governor, (shown in detail in Fig. 3,) which consists of the vertical shaft 18, stepped in the bed-plate, on which shaft is a small pinion 17, meshing with the gear-wheel 10 on the driven shaft. The governor-weights 19 are hung from a collar on the upper end of the shaft 18 and rotated with said shaft, being connected by links of the sliding collar 20. One arm 21 of the bell-crank lever 90 (shown in Fig. 3) has a pad 22, which rubs against the collar 20. This bell-crank is pivoted at 23 in the standard 26. An adjusting-screw 25 bears against the arm 24 of the bell-crank, and thus regulates the pressure of the pad 22 on the collar 20.

95 The operation of my invention is as follows: 100

When the parts are in position, the gear 16^a is slowly driven by the unwinding of the spring 16^b, and such motion is multiplied through the gearing 16, 15, and 14. The driving-gear 14 gives a still higher rate of rotation to the vertical shaft 7 and the table 8, carried thereby, by meshing with the pinion 12 of lesser diameter. The gear 10 rotates with the shaft and gives a very high speed of rotation to the governor-shaft 18. The centrifugal force forces the weights 19 away from the governor-shaft and lifts the collar 20 to a bearing against the pad 22. The more rapidly the machinery rotates the greater this pressure against the pad, so that a limit of speed is soon reached, and this limit can be raised or lowered by adjusting the screw 25.

In assembling the parts of the machine the position of the adjustable frame 2 can be varied by means of the slot and set-screw connections to the bed-plate within quite wide limits until just exactly the right degree of intermeshing between driving-gear 14 and pinion 12 and between gear 10 and governor-pinion 17 is obtained to produce noiseless and easy running. Moreover, by loosening the set-screws 5 and 6 and revolving the frame 2 on the shaft as a center in the direction of the hands of a watch said frame can be entirely disengaged from the set-screws and removed and a duplicate piece of apparatus inserted if the first is found defective or incapable of proper adjustment. The advantage of the invention, as above indicated, consists of its great flexibility of adjustment of parts. The parts 16^a, 16^b, 16, 15, and 14 or their equivalents are called the "driving-gearing." The parts 2 10 11 12 13 or their equivalents are called the "driven gear." The parts 17 18 19 20 21 22 23 24 25 26 or their equivalents are called the "governor."

Of course various changes could be made in the type of gearing, in the form of governor, &c., without departing from the spirit and scope of my invention, so long as the relative arrangement of parts shown in the drawings and the mode of operation set out in the specification are retained.

The shaft 7 may be journaled in the frame 2 in any suitable manner; but I prefer to have a step-bearing of tapering or other shape at its lower end, (not shown,) while the upper end is grooved, as at 29, so that the bearing-plates 27 and 28 may fit into the groove and 55 keep the shaft from lifting out of its lower

bearing. By swinging one of said plates, as 28, around, as shown in dotted lines, Fig. 1, the shaft 7 may be removed from the frame 2.

Having therefore described my invention, what I claim as new, and desire to protect by Letters Patent, is—

1. In a mechanical movement the combination of the driving-gear, the governor, the driven shaft and gearing thereon intermediate of the driving-gearing and the governor and 65 geared to each, and the bearings for said driven shaft adjustable to and from the governor and driving-gearing, substantially as described.

2. In a mechanical movement the combination of the bed-plate, the driving-shaft journaled in said bed-plate, the governor mounted on said bed-plate, the driven shaft intermediate of the driving-shaft and the governor, and geared to each, and the housings 75 for said driven shaft formed in a separate frame, which frame is adjustably mounted on the bed-plate, substantially as described.

3. In a mechanical movement the combination of the bed-plate, the driving-shaft journaled in said bed-plate, the governor mounted on said bed-plate, the driven shaft intermediate of the driving-shaft and the governor, and geared to each, and the housings for said 80 driven shaft, formed in a separate frame, and 85 the slot and set-screw connections between the bed-plate and said frame, substantially as described.

4. The combination of the rotating table, the vertical shaft on which it is mounted, the gear-wheel and pinion on said shaft, the adjustable frame in which said shaft is housed, the bed-plate, the driving-shaft journaled in the bed-plate, and having a gear which meshes with the pinion on the first-mentioned vertical shaft, and the governor mounted on the bed-plate and having a pinion which meshes with the gear on said vertical shaft, substantially as described.

5. The combination of the driving-gearing, 100 the governor, and the driven gear intermediate of the two and adjustable with reference to each, substantially as described.

Signed by me, at New York city, this 8th day of August, 1898.

GEORGE K. CHENEY.
